UNITED STATES PATENT OFFICE

HOWARD A. FLOGAUS, OF DETROIT, MICHIGAN, ASSIGNOR TO RALPH L. SKINNER, OF DETROIT, MICHIGAN

COOLING SYSTEM FOR INTERNAL-COMBUSTION ENGINES

Application filed April 5, 1928. Serial No. 267,493.

My invention relates to novel and advantageous means for cooling internal-combustion engines and particularly their heads, whereby to effectively maintain the engine at 5 a proper operating temperature and to increase the effectiveness of anti-detonating characteristics of the cylinder-heads.

To the attainment of these and other desirable objects, improved means are provided 10 for supplying the cooling liquid to the head sections of the engines and for assuring the draining off of the water in the engine cylinder heads when the water in the main water-jacket is drawn off.

15 To enable those acquainted with this art to have a full and complete understanding of the invention, both from structural and functional standpoints, in the accompanying drawing forming a part of this specification 20 a present, desirable or preferred embodiment of the invention has been illustrated, the same reference characters being used in the various views to designate the same parts of the mechanism.

25 In this drawing:

Figure 1 is a fragmentary, longitudinal, vertical section through the top portion of a multi-cylinder engine incorporating the invention;

30 Figure 2 is a fragmentary cross-section through one of such cylinders; and

Figure 3 is a horizontal section on line 3—3 of Figure 2.

Referring to these drawings, it will be perceived that the several engine cylinders 11 are located inside of an outer casing 12, thereby providing an intervening water-jacket around all of the cylinders, the two inner cylinders of such four-cylinder engine, as 40 shown, being spaced apart somewhat further than the other cylinders.

Each such cylinder has the usual inlet and exhaust ports 14 and 15 respectively, and each cylinder is fitted internally with an 45 inner, stationary cylinder or sleeve 16 spaced inwardly away from the outer cylinder, thereby providing an annular space occupied by two, substantially, semi-circular, sliding valves 17 and 18 reciprocated in any approved 50 manner, as by means of eccentrics, not shown.

Of course, each such valve has an appropriate port therethrough to cooperate with the corresponding intake or discharge port, as the case may be, of the outer cylinder, and the inner cylinder or sleeve is ported in register with the ports of such outer cylinder. 55

Each engine piston 19 slides inside of the complementary cylinder and is joined to the engine crank-shaft by the usual connecting-rod neither of which have been illustrated. 60

The top portion of the inner, stationary cylinder is equipped with a hollow head 21 fitted therein and supplied with an outstanding flange 22 which supports the head and which rests on top of the upper terminal 65 flange of the inner cylinder, which in turn is supported by the cylinder walls.

These overlying flanges are secured in place by any fastenings, such as screws or the like. 70

The under surface of such head or top closure is supplied with a series of abrupt steps or shoulders which act to cause a substantial turbulence in the gaseous explosive mixture in the cylinder, hence securing greater combustion efficiency and avoiding detonation knocks. 75

Each such head has a threaded aperture 23 therethrough for the accommodation of the usual spark-plug 24 which is received in a 80 cavity formed by an upstanding, round wall 25.

The top of the engine is covered by a casing 26 having a water-tight connection with the engine casting, the wall 25 projecting up 85 through a hole in the casing with a liquid-tight joint between them, whereby the spark-plug may be inserted in place and removed without interference with the water chamber formed by such casing and associated parts. 90

At one end, this casing is equipped with a water-discharge pipe or connection 27 leading to the radiator of the vehicle, not shown.

In the water-jacket between the inner cylinders, a vertical pipe 28 is located so that its 95 open lower end will receive relatively cool water as it is delivered to the lower part of the water-jacket in the usual way by the customary water-pump.

At its upper end such pipe connects with 100

the middle portion of a horizontal distribution pipe 31 located longitudinally of the engine above the several cylinder-heads and having closed ends, and a downwardly extended nozzle or branch discharge pipe 32 in each hollow head 21 which delivers its cool water directly on to the upper surface of the stepped bottom wall of the head.

Thus the cup-shaped cylinder-heads, which might otherwise constitute objectionable water pockets, are suitably cooled by constant streams of inflowing cold water directly played against those portions of the heads most likely to become heated in greater degree, and, in this way, the stepped cylinder-heads are adequately cooled to augment and facilitate the performance of their desirable functions of assuring freedom from detonation or too rapid flame propagation, with 20 their incident undesirable noise and injury to bearings.

By having the bottom end of pipe 28 positioned or located lower than the bottoms of the cylinder-heads or lower than the plurality of discharge nozzles, when the water is drained from the jacket, such pipe acts as a siphon to draw off simultaneously practically all of the water in the heads, which might otherwise be trapped therein and freeze during cold weather.

From the foregoing, it should be clear that this novel construction improves and accentuates the desired operation of the shouldered anti-detonating heads and assures proper water drainage.

The invention is not limited to the precise and exact details of construction presented and these may be modified within more or less radical degree without departure from the heart and essence of the invention as defined 40 by the appended claims and without the loss of any of its substantial benefits and advantages.

I claim:

45 1. In an internal-combustion engine, the combination of a cylinder having inlet and exhaust ports, valves controlling said ports, means to operate said valves, a piston reciprocatory in said cylinder, a cup-shaped cylinder-head in said cylinder having a bottom

50 wall with a stepped under surface, a pipe extending into said head and having an outlet directly adjacent to the bottom wall of said head, and means to deliver cooling water through said pipe on to said bottom wall.

55 2. In an internal-combustion engine, the combination of a cylinder having inlet and exhaust ports, valves controlling said ports, means to operate said valves, a cup-shaped cylinder-head in said cylinder, a pipe extending into said head and having an outlet adjacent to the bottom wall of said head, and means to deliver cooling water through said pipe into said head.

60 3. In an internal-combustion engine, the

combination of a cylinder having inlet and exhaust ports, valves controlling said ports, means to operate said valves, a cup-shaped cylinder-head in said cylinder, a delivery pipe extending into said head and having an outlet adjacent to the bottom wall of said head, a feed-pipe connected to said delivery-pipe and extending down beyond the outlet of said delivery-pipe to secure siphon-drainage action, and means to force water through said pipes into said cylinder-heads.

4. In an internal-combustion engine, the combination of a water-jacketed cylinder having inlet and exhaust ports, valves controlling said ports, means to operate said valves, a cup-shaped cylinder-head in said cylinder, a delivery pipe extending into said head and having an outlet adjacent to the bottom wall of said head, a feed-pipe in and receiving water from said water-jacket and connected to said delivery-pipe and extending down beyond the outlet of said delivery-pipe to secure siphon-drainage action, and means to force water into said water-jacket and through said feed and delivery pipes.

In witness whereof I have hereunto set my hand.

HOWARD A. FLOGAUS.
